UNITED STATES PATENT OFFICE.

SHELDON C. CHATHAM, OF PHILADELPHIA, PENNSYLVANIA.

BED-BOTTOM.

1,107,587.

Specification of Letters Patent. Patented Aug. 18, 1914.

Application filed July 9, 1913. Serial No. 778,094.

To all whom it may concern:

Be it known that I, SHELDON C. CHATHAM, a citizen of the United States, residing at Philadelphia, in the county of Philadelphia and State of Pennsylvania, have invented certain new and useful Improvements in Bed-Bottoms, of which the following is a specification.

My invention relates to bed bottoms embodying a side rod, having corner bracket or brackets longitudinally movably mounted thereon, and has particular reference to novel means to effect the longitudinal movement of the corner bracket or brackets and positively prevent them from turning upon the side rod.

An important object of this invention is to provide screw-threaded means, to be attached to the end of the side rod, serving to spline the corner bracket thereto, and dispensing with the necessity of screw-threading the end of the side rod, the means to effect the longitudinal movement of the corner bracket, having screw-threaded engagement with the screw-threaded means.

A further object of my invention is to provide means of the above mentioned character, which are simple in construction, cheap to manufacture, convenient in use, strong and durable.

Other objects and advantages of this invention will be apparent during the course of the following description.

In the accompanying drawings, forming a part of this specification and in which like numerals are employed to designate like parts throughout the same, Figure 1 is a side view of one corner of the bed bottom, showing one corner bracket, Fig. 2 is a central vertical longitudinal sectional view through the corner bracket, Fig. 3 is an inner end view of the same, Fig. 4 is a perspective view of the screw-threaded spline structure, Fig. 5 is a perspective view of the adjusting ring or nut, and, Fig. 6 is an outer end view of the corner bracket.

In the drawings, wherein for the sake of illustration, is shown a preferred embodiment of my invention, the numeral 7 designates a side rod, which is preferably tubular.

The numeral 8 designates a corner bracket, comprising a lower horizontal tubular portion 9, having both ends thereof formed open, as more clearly shown in Fig. 2. This tubular portion 9 is adapted to receive the tubular side rod 7, as shown. Connected

with the upper portion of the corner bracket 8 is a spring mattress 10, of any well known or preferred type.

The numeral 11 designates a screw-threaded spline structure, as a whole, comprising an annular body portion 12, to surround the outer end of the tubular side rod 7 and be rigidly connected therewith by frictional engagement or screws or rivets 13, 60 having their heads flush with the outer surface of the annular body portion 12. This annular body portion 12 carries preferably diametrically oppositely arranged longitudinal splines 14, which engage upon the 70 tubular side rod 7 and have their outer surfaces screw-threaded, as shown at 15. The tubular portion 9 of the corner bracket has the outer end portion of its bore enlarged, such enlarged portion preferably extending 75 to about the point 16, whereby the corner bracket is free to move outwardly and longitudinally of the tubular side rod 7 for a desired distance. The contracted inner portion of the bore of the tubular portion 9 has 80 its inner wall provided with oppositely arranged longitudinal slots 17, for receiving therein the splines 14. It is obvious that these splines will prevent the corner bracket from perceptibly turning upon the tubular 85 side rod.

The numeral 18 designates an operating nut, or ring, having screw-threaded engagement upon the screw-threaded splines 14. Pivotaly connected with this operating nut 90 or ring is a lever or handle 19 adapted to be swung downwardly into engagement with a flange or web 20 of the corner bracket 8, there preferably being a lug 21 disposed upon the opposite side of the lever 19, as 95 shown.

When the different parts of the apparatus are assembled, it is obvious that by rotating the operating nut 18 in the proper direction, the same will effect the outward longitudinal 100 movement of the corner bracket 8, to place the spring mattress 10 under desired tension. By swinging the lever 19 downwardly between the flange or web 20 and the lug 21, the same will positively hold the operating 105 nut 18 against accidental rotation.

It is to be understood that the form of my invention herewith shown and described is to be taken as a preferred example of the same, and that various changes in the shape, 110 size and arrangement of parts may be resorted to without departing from the spirit

of the invention or the scope of the subjoined claims.

Having described my invention, I claim:

5. In apparatus of the character described, the combination with a side rod, of a corner bracket having an opening formed therethrough for receiving the end portion of the side rod to be movable longitudinally thereof, a spring mattress attached to the corner bracket, screw-threaded splines connected with the side rod and operating through openings formed in the corner bracket to positively prevent the same from turning with relation to the side rod but allowing the same to move longitudinally thereof, an operating nut having screw-threaded engagement with the screw-threaded splines, and means to turn the operating nut.
10. In apparatus of the character described, the combination with a side rod, of a corner bracket having an opening formed therethrough for receiving the end portion of the side rod to be movable longitudinally thereof, a spring mattress attached to the corner bracket, splines extending longitudinally of the side rod and attached to the end portion thereof and operating within longitudinal slots formed through the corner bracket to prevent the corner bracket from turning with relation to the side rod, and means having screw-threaded engagement with the splines to effect the longitudinal movement of the corner bracket in one direction.
15. In apparatus of the character described, the combination with a side rod, of a corner bracket having an opening formed therethrough for receiving the end portion of the side rod to be movable longitudinally thereof, a spring mattress attached to the corner bracket, splines extending longitudinally of the side rod and attached to the end portion thereof and operating within longitudinal slots formed through the corner bracket to prevent the corner bracket from turning with relation to the side rod, and means having screw-threaded engagement with the splines to effect the longitudinal movement of the corner bracket in one direction.
20. In apparatus of the character described, the combination with a side rod, of a corner bracket having an opening formed therethrough for receiving the end portion of the side rod to be movable longitudinally thereof, a spring mattress attached to the corner bracket, splines extending longitudinally of the side rod and attached to the end portion thereof and operating within longitudinal slots formed through the corner bracket to prevent the corner bracket from turning with relation to the side rod, and means having screw-threaded engagement with the splines to effect the longitudinal movement of the corner bracket in one direction.
25. In apparatus of the character described, the combination with a side rod, of a corner bracket having an opening formed therethrough for receiving the end portion of the side rod to be movable longitudinally thereof, a spring mattress attached to the corner bracket, splines extending longitudinally of the side rod and attached to the end portion thereof and operating within longitudinal slots formed through the corner bracket to prevent the corner bracket from turning with relation to the side rod, and means having screw-threaded engagement with the splines to effect the longitudinal movement of the corner bracket in one direction.
30. In apparatus of the character described, the combination with a side rod, of a corner bracket having an opening formed therethrough for receiving the end portion of the side rod to be movable longitudinally thereof, a spring mattress attached to the corner bracket, splines extending longitudinally of the side rod and attached to the end portion thereof and operating within longitudinal slots formed through the corner bracket to prevent the corner bracket from turning with relation to the side rod, and means having screw-threaded engagement with the splines to effect the longitudinal movement of the corner bracket in one direction.
35. In apparatus of the character described,

the combination with a side rod, of a tubular element mounted thereon to move longitudinally thereof, a screw-threaded spline attached to the tubular rod and operating within a longitudinal slot formed through the tubular element to positively prevent the same from turning with relation to the side rod and allowing the tubular element to move longitudinally thereof, and an operating nut having screw-threaded engagement with the screw-threaded spline and engaging the tubular element, for effecting the longitudinal movement thereof.

4. In apparatus of the character described, the combination with a side rod, of a corner bracket having an opening formed therethrough for receiving one end of the side rod to be movable longitudinally thereof, a spring mattress attached to the corner bracket, a ring disposed within the opening of the corner bracket and rigidly mounted upon the end portion of the side rod and carrying longitudinally extending screw-threaded splines, an operating nut having screw-threaded engagement with the screw-threaded splines for effecting the longitudinal movement of the corner bracket in one direction, and means to turn the operating nut.

In testimony whereof I affix my signature in presence of two witnesses.

SHELDON C. CHATHAM.
